US0D1082240S

(12) **United States Design Patent** (10) Patent No.: **US D1,082,240 S**
(45) Date of Patent: ** Jul. 8, 2025

(54) **SHOE**

(71) Applicant: **Hongkong Darling Sharrlen Technological Development Co., Limited**, Hong Kong (CN)

(72) Inventor: **Lijun Zheng**, Putian (CN)

(73) Assignee: **Hongkong Darling Sharrlen Technological Development Co., Limited**, Hongkong (CN)

(**) Term: **15 Years**

(21) Appl. No.: **29/985,957**

(22) Filed: **Jan. 17, 2025**

(51) LOC (15) Cl. **02-04**

(52) U.S. Cl.

USPC **D2/916**

(58) **Field of Classification Search**

(57) **CLAIM**

The ornamental design for a shoe, as shown and described.

DESCRIPTION

FIG. 1 is a front perspective view of a shoe, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the shoe, which form no part of the claimed design.

1 Claim, 8 Drawing Sheets
